CONCEALED BED LAMP

Ben Cones, Indianapolis, Ind.

Application August 3, 1946, Serial No. 688,189

6 Claims. (Cl. 240—4)

1

This invention relates to a lamp structure combined with a transverse rail of a bed head piece, and has for a primary object the incorporation of the lamp structure within the rail in such manner that there will be no projected parts beyond the rail other than the switch operating member such as a pull chain. A further primary object of the invention is to provide such a structure that the only alteration required in the rail is the cutting of an aperture therein to permit the insertion of the lamp structure therethrough and the securing of the structure without use of bolts, screws or other like retaining devices. By reason of inclusion of all of the lamp structure as above indicated within the rail, there are no projecting parts that may be accidentally displaced, and yet the illumination is directed forwardly and downwardly as desired.

These and many other objects and advantages of the invention, including the unique combinations of the various elements as set forth in the appended claims permitting easy installation and low cost of production, will become apparent to those versed in the art in the following description of one particular form of the invention as illustrated in the accompanying drawing, in which

Fig. 1 is a view in front elevation of a bed head piece embodying the invention;

Fig. 2, a view in vertical transverse section on the line 2—2 in Fig. 1 on an enlarged scale;

Fig. 3, a view in diametrical section on the line 3—3 in Fig. 2;

Fig. 4, a view in top plan of the lamp and socket holder element; and

Fig. 5, a bottom plan view of a fragmentary length of the head piece top rail through which the switch chain drops.

Referring to the drawing, in which like characters of reference indicate like parts throughout the several views therein, one particular form of a bed head piece 10 is illustrated in Fig. 1 wherein the posts and top rail form one continuous length of tubing 11. In the horizontal length of the tube 11, a rectilinear aperture 12 is formed in any suitable manner to open forwardly and downwardly in relation to the seam 13 of the tube which is generally positioned along the extreme under side thereof in the horizontal length of the tube. A portion at least of the tube is bent inwardly from the forward upper edge of the aperture to form a rectilinear tongue 14 extending around and upwardly in a curving manner spaced from the inner wall of the tube 11.

A socket 15 is selected to have an external 55

2

diameter less than the internal diameter of the tube 11 and is preferably provided with an insulated external wall. A tubular lamp 16 is mounted in this socket 15. The lamp 16 is preferably of that type known as a "show-case" type of lamp being cylindrical in nature and having an external diameter substantially equal to that of the socket 15. The lamp and its socket are detachably carried by a mounting element 17.

The mounting element 17, in the present showing, comprises essentially a shell, arcuate in cross section to have a reflecting surface on its concave side. The element 17 has a foot 18 turned upwardly from the reflecting surface 19 to form an abutment against which the outer end of the socket 15 may rest and be held against longitudinal displacement along the element 17. At the opposite end of the element 17 is a tongue 20 herein shown as having a window 21 therein. The tongue 20 extends outwardly from the reflecting surface 19 a sufficient distance to engage over the outer end of the lamp 16 when secured in the socket 15. The window 21 is provided to permit the curved end of the lamp 16 to project slidably therein or therethrough as a means of not only holding the lamp against longitudinal displacement in the direction of the tongue 20, but also to hold the lamp 16 from lateral displacement from the surface 19. This tongue 20 is preferably elastic so as to yieldingly engage the end of the lamp 16.

Along the opposite edges of the element 17 are a plurality of fingers 22, herein shown as three in number on each side. These fingers 22 curve around to engage over the sides of the lamp 16, with one set of the fingers 22 at least elastically engaging the opposite sides of the socket 15. The lengths of these fingers 22 are in each instance sufficient to grip the lamp 16 and its socket 15 beyond the diametrical plane through the lamp so that over half of the circumference of the lamp 16 lies within the fingers 22. The elasticity of these fingers 22 permits the lamp 16 and socket 15 to be firmly held along the element 17 against the reflecting surface 19 and also permits the removal therefrom, particularly when the lamp 16 has to be replaced.

The radius of curvature of the element 17 exceeds that of the tube 11. The fingers 22 are given a much shorter radius of curvature than that of the wall of the element 17 in order that they will initially be spaced oppositely one from the other a distance between their outer ends requiring them to be sprung apart upon the removal of the lamp 16 and reinsertion of the lamp

between those fingers. A second set of fingers 23, at least two on each side of the element 17 and extending from the edges thereof, is provided. These fingers 23 have a radius of curvature at least equaling that of the element 17, and preferably more. These fingers 23 are elastic and in the nature of springs. They are spaced apart longitudinally along the element 17, one finger 23 from the other on the same edge respectively a distance approaching but somewhat less than that of the longitudinal length of the tongue 14.

The element 17 may be secured in position within the tube 11 before mounting of the lamp and its socket 15 thereon, or the lamp 16 and its socket 15 may initially be mounted on the element 17 to be there secured as above indicated before positioning that assembly within the tube 11.

Assuming that the assembly of the lamp, socket, and the element 17 has been initially made, the cord 24 leading from the socket 15 is threaded through the tube 11 from the aperture 12 and around inside of the tube to any desired position of outlet, herein shown as on one of the posts 25 where the cord 24 is carried outwardly from the side of the post to have a plug connector 26 thereon. The socket 15 end of the assembly is then inserted through the aperture 12 to have the whole assembly entered within the tube 11. This assembly is pressed inwardly toward the inside face of the tube 11 opposite the aperture 12 to have the pull chain 27 carried downwardly through a hole 28 initially provided in the under side of the tube 11. The pull chain 27 leads from the socket 15 to operate the switch therein all in the usual manner, the socket 15 being of the pull chain switch type well known to those versed in the art, and hence the details thereof are not herein illustrated. The assembly above indicated is revolved within the tube 11 to have the upper fingers 23 enter under the lip 14 whereupon the assembly is then revolved in a counter-clockwise direction in respect to Fig. 2, to have the lower fingers 23 drop down behind the seam 13. To effect this position of these fingers 23, the assembly is pushed inwardly bodily to allow these fingers 23 to spring in behind that seam 13 while the upper fingers 23 are held under the lip 14. The assembly is longitudinally aligned in reference to the aperture 12 to have the lamp 16 therebehind. The assembly is held against longitudinal displacement along the tube 11 under any pull on the cord 24 by employing an abutment such as a foot 29 extending from one of the fingers 23 adjacent the tongue 20 to abut the lateral edge of the lip 14. Preferably the aperture 12 is closed over by some transparent material such as by a sheet of transparent plastic 30, the inner edges 31 and 32 of which are sprung inwardly and under the opposing longitudinal edges of the aperture 12 with the longitudinal ends 33 and 34lapping over on the outer surface of the tube 11.

Thus it is to be seen that a simply constructed but quite efficient mounting of a lamp is provided to carry that lamp entirely within the tube 11 without having to employ any screws or bolts or any other like means. The holding element 17 is simply elastically engaged within the tube to be held in a substantially rigid position permitting quick assembly of the unit and also permitting easy replacement of the lamp 16. While I have herein shown and described the invention in the one particular form, it is obvious that structural details may be varied without departing from the spirit of the invention, and I therefore do not de-

sire to be limited to that precise form beyond the limitations which may be imposed by the following claims.

I claim:

- 5 1. For mounting a lamp and socket, the combination with a horizontally disposed bed head piece hollow rail having a longitudinally disposed aperture therein; a lip inturned in a direction away from a longitudinal edge of the aperture to have the inner end of this lip spaced from the rail wall; a lamp and socket mounting element; fingers extending from the element to elastically engage about a lamp and socket to be carried by the element; and fingers extending from an edge of the element adapted, upon body rotation of the element within the rail, to enter under said lip.
- 10 2. For mounting a lamp and socket, the combination with a horizontally disposed bed head piece hollow rail having a longitudinally disposed aperture therein; a lip inturned in a direction away from a longitudinal edge of the aperture to have the inner end of this lip spaced from the rail wall; a lamp and socket mounting element; fingers extending from the element to elastically engage about a lamp and socket to be carried by the element; and fingers extending from an edge of the element adapted, upon body rotation of the element within the rail, to enter under said lip; said rail having an internal abutment spaced circumferentially around from said lip; and means carried by said element to drop behind said abutment to hold said element against reverse rotation to maintain said lip engaging fingers under said lip.
- 15 3. For mounting a lamp and socket, the combination with a horizontally disposed bed head piece hollow rail having a longitudinally disposed aperture therein; a lip inturned in a direction away from a longitudinal edge of the aperture to have the inner end of this lip spaced from the rail wall; a lamp and socket mounting element; fingers extending from the element to elastically engage about a lamp and socket to be carried by the element; and fingers extending from an edge of the element adapted, upon body rotation of the element within the rail, to enter under said lip; said rail having an internal abutment spaced circumferentially around from said lip; and means carried by said element to drop behind said abutment to hold said element against reverse rotation to maintain said lip engaging fingers under said lip.
- 20 4. For mounting a lamp and socket, the combination with a horizontally disposed bed head piece hollow rail having a longitudinally disposed aperture therein; a lip inturned in a direction away from a longitudinal edge of the aperture to have the inner end of this lip spaced from the rail wall; a lamp and socket mounting element; fingers extending from the element to elastically engage about a lamp and socket to be carried by the element; and fingers extending from an edge of the element adapted, upon body rotation of the element within the rail, to enter under said lip; said rail having an internal abutment spaced circumferentially around from said lip; and means carried by said element to drop behind said abutment to hold said element against reverse rotation to maintain said lip engaging fingers under said lip.
- 25 5. For mounting a lamp and socket, the combination with a horizontally disposed bed head piece hollow rail having a longitudinally disposed aperture therein; a lip inturned in a direction away from a longitudinal edge of the aperture to have the inner end of this lip spaced from the rail wall; a lamp and socket mounting element; fingers extending from the element to elastically engage about a lamp and socket to be carried by the element; and fingers extending from an edge of the element adapted, upon body rotation of the element within the rail, to enter under said lip; said rail having an internal abutment spaced circumferentially around from said lip; and means carried by said element to drop behind said abutment to hold said element against reverse rotation to maintain said lip engaging fingers under said lip.
- 30 6. For mounting a lamp and socket, the combination with a horizontally disposed bed head piece hollow rail having a longitudinally disposed aperture therein; a lip inturned in a direction away from a longitudinal edge of the aperture to have the inner end of this lip spaced from the rail wall; a lamp and socket mounting element; fingers extending from the element to elastically engage about a lamp and socket to be carried by the element; and fingers extending from an edge of the element adapted, upon body rotation of the element within the rail, to enter under said lip; said rail having an internal abutment spaced circumferentially around from said lip; and means carried by said element to drop behind said abutment to hold said element against reverse rotation to maintain said lip engaging fingers under said lip.
- 35 7. For mounting a lamp and socket, the combination with a horizontally disposed bed head piece hollow rail having a longitudinally disposed aperture therein; a lip inturned in a direction away from a longitudinal edge of the aperture to have the inner end of this lip spaced from the rail wall; a lamp and socket mounting element; fingers extending from the element to elastically engage about a lamp and socket to be carried by the element; and fingers extending from an edge of the element adapted, upon body rotation of the element within the rail, to enter under said lip; said rail having an internal abutment spaced circumferentially around from said lip; and means carried by said element to drop behind said abutment to hold said element against reverse rotation to maintain said lip engaging fingers under said lip.
- 40 8. For mounting a lamp and socket, the combination with a horizontally disposed bed head piece hollow rail having a longitudinally disposed aperture therein; a lip inturned in a direction away from a longitudinal edge of the aperture to have the inner end of this lip spaced from the rail wall; a lamp and socket mounting element; fingers extending from the element to elastically engage about a lamp and socket to be carried by the element; and fingers extending from an edge of the element adapted, upon body rotation of the element within the rail, to enter under said lip; said rail having an internal abutment spaced circumferentially around from said lip; and means carried by said element to drop behind said abutment to hold said element against reverse rotation to maintain said lip engaging fingers under said lip.
- 45 9. For mounting a lamp and socket, the combination with a horizontally disposed bed head piece hollow rail having a longitudinally disposed aperture therein; a lip inturned in a direction away from a longitudinal edge of the aperture to have the inner end of this lip spaced from the rail wall; a lamp and socket mounting element; fingers extending from the element to elastically engage about a lamp and socket to be carried by the element; and fingers extending from an edge of the element adapted, upon body rotation of the element within the rail, to enter under said lip; said rail having an internal abutment spaced circumferentially around from said lip; and means carried by said element to drop behind said abutment to hold said element against reverse rotation to maintain said lip engaging fingers under said lip.
- 50 10. For mounting a lamp and socket, the combination with a horizontally disposed bed head piece hollow rail having a longitudinally disposed aperture therein; a lip inturned in a direction away from a longitudinal edge of the aperture to have the inner end of this lip spaced from the rail wall; a lamp and socket mounting element; fingers extending from the element to elastically engage about a lamp and socket to be carried by the element; and fingers extending from an edge of the element adapted, upon body rotation of the element within the rail, to enter under said lip; said rail having an internal abutment spaced circumferentially around from said lip; and means carried by said element to drop behind said abutment to hold said element against reverse rotation to maintain said lip engaging fingers under said lip.
- 55 11. For mounting a lamp and socket, the combination with a horizontally disposed bed head piece hollow rail having a longitudinally disposed aperture therein; a lip inturned in a direction away from a longitudinal edge of the aperture to have the inner end of this lip spaced from the rail wall; a lamp and socket mounting element; fingers extending from the element to elastically engage about a lamp and socket to be carried by the element; and fingers extending from an edge of the element adapted, upon body rotation of the element within the rail, to enter under said lip; said rail having an internal abutment spaced circumferentially around from said lip; and means carried by said element to drop behind said abutment to hold said element against reverse rotation to maintain said lip engaging fingers under said lip.
- 60 12. For mounting a lamp and socket, the combination with a horizontally disposed bed head piece hollow rail having a longitudinally disposed aperture therein; a lip inturned in a direction away from a longitudinal edge of the aperture to have the inner end of this lip spaced from the rail wall; a lamp and socket mounting element; fingers extending from the element to elastically engage about a lamp and socket to be carried by the element; and fingers extending from an edge of the element adapted, upon body rotation of the element within the rail, to enter under said lip; said rail having an internal abutment spaced circumferentially around from said lip; and means carried by said element to drop behind said abutment to hold said element against reverse rotation to maintain said lip engaging fingers under said lip.
- 65 13. For mounting a lamp and socket, the combination with a horizontally disposed bed head piece hollow rail having a longitudinally disposed aperture therein; a lip inturned in a direction away from a longitudinal edge of the aperture to have the inner end of this lip spaced from the rail wall; a lamp and socket mounting element; fingers extending from the element to elastically engage about a lamp and socket to be carried by the element; and fingers extending from an edge of the element adapted, upon body rotation of the element within the rail, to enter under said lip; said rail having an internal abutment spaced circumferentially around from said lip; and means carried by said element to drop behind said abutment to hold said element against reverse rotation to maintain said lip engaging fingers under said lip.
- 70 14. For mounting a lamp and socket, the combination with a horizontally disposed bed head piece hollow rail having a longitudinally disposed aperture therein; a lip inturned in a direction away from a longitudinal edge of the aperture to have the inner end of this lip spaced from the rail wall; a lamp and socket mounting element; fingers extending from the element to elastically engage about a lamp and socket to be carried by the element; and fingers extending from an edge of the element adapted, upon body rotation of the element within the rail, to enter under said lip; said rail having an internal abutment spaced circumferentially around from said lip; and means carried by said element to drop behind said abutment to hold said element against reverse rotation to maintain said lip engaging fingers under said lip.
- 75 15. For mounting a lamp and socket, the combination with a horizontally disposed bed head piece hollow rail having a longitudinally disposed aperture therein; a lip inturned in a direction away from a longitudinal edge of the aperture to have the inner end of this lip spaced from the rail wall; a lamp and socket mounting element; fingers extending from the element to elastically engage about a lamp and socket to be carried by the element; and fingers extending from an edge of the element adapted, upon body rotation of the element within the rail, to enter under said lip; said rail having an internal abutment spaced circumferentially around from said lip; and means carried by said element to drop behind said abutment to hold said element against reverse rotation to maintain said lip engaging fingers under said lip.

under said lip; and means carried by said element to hold said lamp and socket thereon against longitudinal displacement.

5. For mounting a lamp and socket, the combination with a horizontally disposed bed head piece hollow rail having a longitudinally disposed aperture therein; a lip inturned in a direction away from a longitudinal edge of the aperture to have the inner end of this lip spaced from the rail wall; a lamp and socket mounting element; fingers extending from the element to elastically engage about a lamp and socket to be carried by the element; and fingers extending from an edge of the element adapted, upon body rotation of the element within the rail, to enter under said lip; said rail having an internal abutment spaced circumferentially around from said lip; and means carried by said element to drop behind said abutment to hold said element against reverse rotation to maintain said lip engaging fingers under said lip; and means carried by said element to hold said lamp and socket thereon against longitudinal displacement; and means holding said element against longitudinal displacement in at least one direction.

6. For mounting a lamp and socket, the combination with a horizontally disposed bed head piece hollow rail having a longitudinally disposed aperture therein; a lip inturned in a direction away from a longitudinal edge of the aperture to have the inner end of this lip spaced from the rail wall; a lamp and socket mounting element; fingers extending from the element to elas-

tically engage about a lamp and socket to be carried by the element; and fingers extending from an edge of the element adapted, upon body rotation of the element within the rail, to enter under said lip; said rail having an internal abutment spaced circumferentially around from said lip; and means carried by said element to drop behind said abutment to hold said element against reverse rotation to maintain said lip engaging fingers under said lip; and means carried by said element to hold said lamp and socket thereon against longitudinal displacement; and means holding said element against longitudinal displacement in at least one direction; said last means comprising an arm carried by one of said fingers extending in the path of a circumferential edge of said lip.
